SIDE STAKE POCKET FOR CARS

Roy A. Lewis, Bethlehem, and Charles Schenck,
Coopersburg, Pa., assignors to Bethlehem Steel
Company, a corporation of Pennsylvania

Original application March 20, 1936, Serial No.
69,846. Divided and this application March 29,
1937, Serial No. 133,558

11 Claims. (Cl. 105—390)

This invention relates to flat car underframe structures or the like for railway cars, and is particularly directed to the stake pockets and the arrangement and manner of forming and attaching said stake pockets to the underframe structure, and is a division of our copending application entitled "Stake pocket for cars", filed March 20, 1936, Serial No. 69,846.

The stake pockets for receiving the lower ends of the stakes in position in spaced relation along the sides and ends of the car have been formed heretofore of cast or pressed metal and usually attached to the flat side surfaces of the side or end sills of the car underframe by means of bolts or rivets. When the car is loaded the stake pockets are subjected to enormous strain produced by the leverage pressure of the lading on the extending stakes of the car, which results in the connections of the stake pockets with the underframe becoming loose, or the stake pockets breaking off. The loosening of the stake pockets further has the disadvantage of allowing moisture to collect around the bolted or riveted connections thereby allowing corrosion to set in very rapidly.

One of the objects of our invention relates to forming the stake pockets of rolled sheet metal adapted to be attached directly to the car underframe by welding.

Another object of our invention relates to forming the stake pockets in such a manner that they will be more securely braced when attached to the car underframe.

A further object of our invention resides in the manner of reinforcing the intermediate portion of the stake pocket.

Another object of our invention is to provide a stake pocket that can be attached to a flanged or flat surface of the car underframe.

Having thus given a general description of the objects of our invention we will now in order to make the invention more clear refer to the accompanying two sheets of drawings which form a part of this specification and on which like characters of reference indicate like parts:

Figure 1 is a top plan view of slightly more than one-half of a car underframe illustrating the application of our invention.

Fig. 2 is a detail top plan view of a portion of a car side sill with one of our improved stake pockets attached thereto drawn on a larger scale.

Fig. 3 is a longitudinal section of the portion shown in Fig. 2 taken on the line 3—3 of Fig. 4.

Fig. 4 is a side elevation of the enlarged portion shown in Fig. 2.

Fig. 5 is a vertical section taken on the line 5—5 of Fig. 4, and

Fig. 6 is a vertical section through the end sill 5 taken on the line 6—6 of Fig. 1.

Referring now to the various characters of reference on the drawings the numeral 1 indicates the car underframe as a whole, 2 the center sills, 3 the side sills, 4 the bolster, 5 the cross ties or 10 bearers and 6 a cover plate attached to the top edge of the end sill 7 and adapted to extend inwardly therefrom and provided with a flanged edge as at 8, the lower end of which is bent inwardly at right angles thereto and adapted to 15 form a seat for supporting the end of the car floor.

As illustrated in the drawings the side sills 3 are constructed of rolled I-sections with flanges 9 20 extending laterally therefrom along the top and bottom edges, although these side sill members may be of other section, as channels, Z-bars, or angles, or they may be made of pressed or of cast metal if desired without departing from the 25 spirit of our invention.

The stake pockets attached to the side sills 3 of the underframe at spaced intervals are formed or rolled pressed sheet metal, each having a U-shaped portion 10 forming the stake pocket, the legs 11 of which are parallel for a portion of 30 their length and connected together by a reinforcing rib 12, which is welded to the legs 11 as at 13. The ends of the legs 11 are formed with outwardly inclined or splayed extensions 14 having 35 their ends welded to the web of the side sill as at 15. The upper surfaces of the leg extensions 14 are inclined, or shaped to conform to the contour of the underside of the upper outwardly extending flange of the side sill and is 40 welded thereto as at 16.

In forming the extensions 14 of the legs splayed in the manner shown, a more desirable bracing effect is obtained than if the legs were made straight for the entire length. To further stiffen 45 and brace the stake pockets laterally, brackets 17 formed of plate metal are welded to the opposite sides of the pockets at an intermediate point as at 18, the inner ends of said brackets being welded as 50 at 19 to the top of the side sills 3. By this construction a very strong and rigid construction is obtained, the stake pockets being substantially 55 integrally connected to the side sills will not become loose and allow moisture to collect and

produce corrosion between the connections as in the case where bolts or rivets are used.

The stake pockets 20 at the ends of the car are formed and attached in a somewhat different manner. These stake pockets are U-shaped, the legs being parallel to each other throughout their entire length. The ends of the legs are welded as at 21 directly to the inner face of the end sill 7, the rear end of the stake pockets engaging the vertical wall of the flange 8 of the cover plate 6 and welded thereto as at 22.

Openings 23 are formed in the cover plate 6, which registers with the stake pockets. The upper end of the stake pockets are adapted to engage the under side of the cover plate 6 and is welded thereto as at 24.

In this construction a very rigid connection is obtained and the stake pockets are securely held in position between the rear wall of the end sill 7 and the vertical wall of flange 8. The sides 20 of the openings 23 in the cover plate 6 further help to support the stake when in position.

As illustrated the stake pockets are formed of pressed metal, but they can be formed of cast metal if desired and then welded to the under-frame in the manner above described.

Although we have shown and described our invention in considerable detail, we do not wish to be limited to the exact construction shown and described, but may use such substitutions, modifications or equivalents thereof, as are embraced within the scope of our invention, or as pointed out in the claims.

Having thus described our invention what we claim as new and desire to secure by Letters Patent is:

1. A car underframe, the combination with the side sills of rolled section each having a vertical web and an outwardly extending upper flange, a stake pocket formed of pressed metal comprising 40 a substantially U-shaped body portion extending above the outwardly extending upper flanges of the side sills having splayed leg extensions having their inner and upper edges welded to the web and under surface of the outwardly extending flange of the side sills, separate reinforcing flanges welded to the top of the side sills and the sides of the U-shaped body portion of the stake pocket above the side sills, and a plate connection between the legs of the U-shaped body portion welded to the outer edge of the upper flange of the side sills.

2. A car underframe, the combination with the side sills of rolled I-section each having a vertical web and laterally extending upper and lower flanges, a stake pocket formed of pressed metal comprising a substantially U-shaped body portion extending above the side sills having splayed leg extensions having their inner and top edges welded to the web and under surface of the outwardly extending flange of the side sills, separate reinforcing plate flanges welded to the opposite sides of the U-shaped body portion of the stake pocket above the side sills, and a plate connecting 60 the legs of the U-shaped body portion of the stake pocket at an intermediate point having its ends welded to the legs and the flanged outer edge of the side sill.

3. A car underframe, the combination with the side sills of rolled section each having a vertical web and an outwardly extending upper flange, of stake pockets of pressed metal extending above the side sills having inclined leg portions having the inner and upper edges of their 70 legs welded to the web and the underside of the

outwardly extending flange of the side sills, and brackets formed of plate metal welded to the upwardly extending top portions of the stake pockets and the top of the side sills for reinforcing the stake pockets above the side sills.

4. A car underframe, the combination with the side sills of rolled section each having a vertical web and an outwardly extending upper flange, of U-shaped stake pockets formed of pressed plate metal extending above the side sills having the ends of their legs inclined outwardly and the inner and top edges welded to the web and outwardly extending flange of the side sills, and separate reinforcing plates welded to the top of the side sills and to opposite sides of the upwardly extending portions of the stake pockets.

5. A car underframe, the combination with the side sills of rolled section each having a vertical web and an outwardly extending upper flange, of U-shaped stake pockets each formed of pressed 20 plate metal extending above the side sills, bracket plates welded to the tops of the side sills and the upwardly extending portions of the U-shaped stake pockets, said U-shaped stake pockets having splayed leg extensions having their inner and upper edges welded to the web of the side sills and the under surface of the outwardly extending flange.

6. A car underframe, the combination with the side sills of rolled section each having a vertical 30 web and an outwardly extending upper flange, a stake pocket of plate metal comprising a substantially U-shaped body portion extending above the side sills with splayed leg extensions welded at its inner and upper edges to the web and outwardly extending flange of the side sills, and separately formed reinforcing plates above the side sills welded to the sides of the U-shaped body portion of the stake pocket and the top surfaces of the side sills.

7. A car underframe, the combination with the side sills each formed of a separate rolled section having a vertical web and an outwardly extending upper flange, stake pockets each having a U-shaped body portion formed of pressed plate 45 metal adapted to extend above the side sills, said U-shaped stake pockets having splayed leg extensions extending inwardly from the U-shaped pockets with their inner and upper edges welded to the web and outwardly extending under surfaces of the flange of the side sills, a plate connecting the intermediate portions of the legs of the U-shaped body portion of each stake pocket and having its ends welded to the legs and the flanged outer edge of the side sill, and reinforcing flanges welded to the opposite sides of the U-shaped body portion and to the top of the side sills.

8. A car underframe, the combination with the side sills of I-section each having a web and flanged edges, stake pockets each having a U-shaped body portion formed of pressed plate metal adapted to extend above the side sills, said U-shaped stake pockets having splayed leg extensions adapted to project under a flange of the side sills, said splayed leg portions having their inner and top edges welded to the web of the side sills and the lower surface of the flange, and a plate connecting the legs of the U-shaped body portion and the outer edge of the flange and secured thereto.

9. A car underframe, the combination with the side sills each having a web and flanged edges, stake pockets each having a U-shaped body portion formed of pressed plate metal, said U-shaped 75

stake pockets extending above the side sills and having splayed leg extensions adapted to project under the top flange of the side sill, said splayed leg extensions having their inner and upper edges welded to the web and lower surface of the top flange of the side sill, a plate connecting the intermediate portions of the legs of each of the U-shaped body portions of the stake pocket and having its ends welded thereto, and the outer edge of the flange of the side sills, and reinforcing plate flanges welded to opposite sides of the U-shaped body portion having their inner edges engaging the top of the side sill and welded thereto.

10. A car underframe, the combination with the side sill having a web and an outwardly extending top flange, U-shaped side stake pockets extending above the side sill formed of pressed plate metal having the ends of their legs inclined outwardly and the inner and top edges welded to the web and outwardly extending under sur-

face of the top flange of the side sill, and a plate integrally connecting the intermediate portions of the U-shaped legs of each side stake pocket and the outer edge of the flange of the side sill, and plate flanges above the side sills welded to 5 the U-shaped body portion of the stake pocket and secured to the top of the side sill.

11. A car underframe, the combination with the side sill of rolled section having a vertical web and an outwardly extending flanged upper 10 edge, a stake pocket extending above the side sill having laterally extending splayed leg extensions having their inner and upper edges welded to the web and the underside surface of the outwardly extending flange of the side sill, and reinforcing 15 flanges above the side sill welded to each of the stake pockets and the top of the flanged edge of the side sill.
